CHESTER A. RATEKIN, OF KANSAS CITY, MISSOURI.

LACING STRUCTURE.

1,205,109.

Specification of Letters Patent. Patented Nov. 14, 1916.

Application filed November 9, 1914. Serial No. 871,101.

To all whom it may concern:

Be it known that I, CHESTER A. RATEKIN, a citizen of the United States, residing at Kansas City, in the county of Jackson and State of Missouri, have invented certain new and useful Improvements in Lacing Structures, of which the following is a full, clear, and exact description.

This invention relates to lacing structures, and particularly to a lacing construction which is especially adapted for use in connection with foot-wear, and the principal object of the invention is to devise a lacing combination which will not only have all the advantages of a quickly and easily operated lacing, but also, what is of still greater importance and advantage as regards the object hereby sought to be attained, afford a high degree of neatness in the appearance of the shoe closure and of comfort to the wearer. For this purpose a structure has been produced whereby the tension of the lacing is distributed substantially equally along the edges of the laced material with the result that the upper of the shoe is drawn uniformly into place without undue stress or pull on any portion thereof, and the possibility of the formation of permanent unsightly wrinkles is prevented. It is also sought to contrive a lacing construction of extreme simplicity, such that its introduction into the manufacture of the usual type of lace-shoe may be made with but little alteration or expense.

With the above general object in view, the invention comprises certain novel features of construction and combinations of parts, the essential elements of which are set forth in the appended claims, and various forms of embodiment of which are hereinafter specifically described with reference to the drawing accompanying and forming a part of this specification.

In the drawing, Figure 1 is a perspective view illustrating a shoe embodying the invention; Fig. 2 is a fragmentary plan view (on a larger scale) showing one form of the lacing structure, the dotted lines representing the concealed or blind lacing loops or members; Fig. 3 is a plan view of alternative forms of lacing loops or members adapted for use in the construction indicated in Fig. 2; Fig. 4 is a section on the line 4—4 of Fig. 2; Fig. 5 is a similar section but showing a modified form of piping; Fig. 6 is a fragmentary plan view of an-

other form of the lacing construction embodying a different type of blind lacing loops or members; Fig. 7 is a section on the line 7—7 of Fig. 6; Fig. 8 is a fragmentary back plan view of a still further modified construction; and Fig. 9 is a section on the line IX—IX of Fig. 8.

Referring to the drawing, this shows slightly different forms of embodiment of the invention, the essential elements of which, however, remain the same in each modification. In Figs. 2 and 4 is illustrated a form in which the upper portions 2 of the shoe 4 are provided with pipings 6 at opposite sides of the usual closure slit 6, each of these pipings being formed by means of front and back stay pieces 8 secured to the corresponding upper portion by a row of stitching 10 and to each other by a row of stitching 12. The edges of the stays at the stitching 12 project past the edges of the upper and form the margins of the slit 6. Within these pipings are secured by means of stitching 14 a series of blind lacing loops or members 16, each embracing opposite sides of the corresponding upper edge and forming a lacing passage 18 directly opposite said edge and extending longitudinally of the slit 6. These lacing members 16 may be in the form of separate loops, or each series may be stamped from a single blank to form a chain of such loops, as shown in Fig. 3, to facilitate their manufacture and secure proper and accurate spacing of the members. The outer stay piece 8 is provided with a series of lacing openings 20 at points opposite the openings into the several loop passages 18 to receive the lacing string 22.

In the modified form illustrated in Fig. 5, only one stay piece 8 is employed in connection with each upper edge to form the piping, stitching 24 being used to secure said upper edge to one edge of the stay piece 8 along the margin of the slit 6. The lacing members or loops 16 are then secured by means of stitching 26 within the piping thus formed, and lacing openings 20 are provided in the upper 2 adjacent the stitching 24 in the same manner as in the outer stay 8 of the structure first described.

In the modification illustrated in Figs. 6 and 7 use is made of metallic lacing or loop members 28 inclosed within pipings formed by front and back stays 8 secured to the upper portions in the same manner as before.

described. Each metal member 28 comprises a flat body portion provided with spaced clenching eyelets 30 for securing the member to the upper, and a hook portion 32 projecting past the edge of the upper and extending in the same direction as the eyelet portions so as to be located directly opposite the edge of the upper and form a lacing passage 18 parallel therewith. The securing eyelets 30 are spaced apart a distance at least equal to the length of the hook portions 32, in order that the pull of the lacing cord 22, which is passed through the passages 18 and openings 20 in the outer stay 8, will not be confined to any too restricted area but will be distributed as evenly as possible the full length of the closure slit. Obviously the lacing members 28 may be secured on either the inner or the outer face of the upper edge, and the clenching eyelets are spaced so as to occur at about the same intervals as the usual lacing eyelets of an ordinary shoe. The edges of the hook portions 32 are slightly rounded off, as shown, so as not to damage the lacing cord 22.

In Figs. 8 and 9 is shown a structure in which the edge of the upper forming each side of the closure slit is folded back and stitched as shown at 34, so that the folded edge of the upper presents a continuous shoulder against which abuts the series of lacing members 16, the latter constructed and secured substantially as illustrated in Fig. 5 excepting that the back stay piece 8 may or may not be employed, since the ordinary upper lining (not shown) will meet the requirements in this respect. Lacing openings 20 are provided in the upper at the proper intervals as in the previous construction. The advantage of this modification lies in the fact that the folded edge of the upper tends to reinforce the loops along the passages 18 and resist any tendency of the loops to draw out of shape; and this structure also has the advantage of being extremely compact by reason of the parts being reduced to a minimum number of layers or thicknesses.

In all of the foregoing forms it will be apparent that the essential elements of the lacing structure remain in substantially the same combination, the object being to provide a closure in which the parts will comprise neat straight edges, and concealed or blind rigidly-secured lacing members or loops having lacing passages extending parallel with the closure slit, so that the pull on the lacing cord will draw the slit edges neatly together, or at any rate in smooth-lying and uniformly parallel lines, without any wrinkling or buckling of the adjacent upper portions. It is furthermore obvious that the principal advantages of such an arrangement, outside the fact that the lacing operation is quick and easy, are in the neat-

ness of the appearance of the closure when laced, and its great comfort to the foot. For each loop or lacing member, when the shoe is made up with any one of the above forms, occupies the space of two of the ordinary shoe eyelets, whereby the number of crosses of the lacing cord is reduced, and as a consequence, the surplus in the tying ends of the lacing cord is eliminated; and, with only four crosses of the lacing cord for the average height of upper and with the lacing passages 18 arranged parallel with the slit, friction is also greatly reduced, so that the lacing is operated with extreme ease and with very little wear on the cord. The humping of the leather between adjacent loops or lacing members is prevented by securing the loops or lacing members to the upper for a distance equal to or greater than the length of each of the lacing passages 18, and by this means the formation of permanent wrinkles is avoided, which in turn prevents openings along the edges of the closure through which dust, etc., would otherwise be admitted. The manner of securing the loops or lacing members also gives a secure fastening with very little strain on the upper leather, and provides a means whereby it is possible to exert a lacing pull in substantially the same plane as the edge of the upper at the slit for the purpose, as above indicated, of equalizing the pull along said edge throughout the entire length of the slit, and to the end also of obtaining a more comfortably fitting closure. This comfort is increased, moreover, by the fact that the edge of the upper along the slit is kept as thin as possible, and also by the important fact that the lacing cord is not allowed to pass through and under the upper into binding contact with either the foot or the tongue of the shoe, since in the present construction the lacing cord never passes beneath the lacing passages 18. Again, by having the pull exerted as nearly as possible in the same plane as that of the edge of the upper at the slit, this eliminates any binding action of the lacing cord in a direction to cause said edge of the upper to bite into the tongue of the shoe, which always tends to bunch up the tongue and render it impossible to obtain a smooth-lying closure.

While the foregoing represents what have been found to be suitable and practical forms of embodiment of the invention, the right is reserved to such formal changes and modifications as may fairly fall within the scope of the claims which follow.

Claims:

1. A lacing structure comprising members each having an edge portion provided with spaced lacing openings, and a lacing element secured to each of said members between the lacing openings thereof, said lacing elements being shaped to form lacing

passages having their axes arranged in a line extending parallel with the edges of said members respectively, and the ends of said lacing passages registering with the corresponding lacing openings.

2. A lacing structure comprising members having portions providing a closure slit, and a series of lacing elements secured to said members beneath the same and concealed thereby, said elements being shaped to form lacing passages having their axes arranged in a line extending longitudinally of said slit, and said members having lacing openings registering with the ends of each of said lacing passages.

3. A lacing structure comprising members having portions providing a closure slit, said members each having a series of spaced lacing openings, and a series of lacing elements secured to said members between said openings, said elements being shaped to form lacing passages having their axes arranged in a line extending longitudinally of said slit and the ends of each of said lacing passages registering with said lacing openings.

4. A lacing structure comprising members having edges forming a closure slit, said

members having marginal strip portions reinforcing the edges of said slit and forming shoulders extending longitudinally of the slit, and a series of lacing elements secured to said members and provided with lacing passages, said lacing elements abutting against said shoulders and thereby reinforcing said lacing passages, said members being provided with lacing openings registering with the ends of said lacing passages.

5. A lacing structure comprising members having portions providing a closure slit, said members being doubled back along said slit and secured to reinforce the margins of the slit and form longitudinal shoulders adjacent said slit, and a series of elements secured to said members and provided with lacing passages, said elements abutting against said shoulders and thereby reinforcing said lacing passages, and said members having lacing openings registering with the ends of said passages.

In witness whereof I affix my signature in the presence of two witnesses.
